FRACTURE SLING

Norman A. Fleishman, Muskegon, Mich.

Application April 21, 1947, Serial No. 742,910

1 Claim. (Cl. 128—84)

1

The present invention relates to a fracture sling and more particularly to a sling adapted to maintain the position of reduction of a fractured vertebra during the application of any suitable immobilizing agent such as that commercially known as "Air-Lite," manufactured and sold by the Tower Company, Seattle, Washington.

The primary objects of the instant invention are to provide a fracture sling of the general character above indicated whereby a cast may be closely fitted to a patient suffering from the fracture of the vertebra at the upper point of any of the three points of fixation to thereby obtain reduction, which three points are (1) the pelvic brim anteriorly, (2) the site of fracture posteriorly, and (3) the region of the sternal notch anteriorly and superiorly; to provide such a fracture sling whereby the three points referred to above permit the retention of the necessary extension of the patient; to provide such a fracture sling whose opposite ends may be both either elevated and/or dropped and lengthened or shortened to increase or decrease the degree and character of arch of the vertebra of the patient; to provide such a fracture sling having a secondary sling adapted to allow the arms of the patient to remain in a position of comfort not greater than 90 degrees abduction to thereby permit a close fitting of the application of the cast without extension of the scapulae and latissimus dorsi muscles; to provide such a fracture sling which is highly efficient and convenient in its intended use; and, to provide such a fracture sling which is reasonably economical in manufacture.

An illustrative embodiment of the invention is shown in the accompanying drawings, wherein:

Figure 1 is a side elevational view of the sling and its supporting frame showing the patient selectively slung in one position prior to the fitting of the cast;

Figure 2 is a view similar to Figure 1 but showing the patient selectively slung in a different position;

Figure 3 is a top plan view of the sling and its supporting frame, partly broken away at its foot end;

Figure 4 is a fragmentary head end view of the sling and its supporting frame, partly in section; and

Figure 5 is a plan view of the sling per se.

Referring then to the drawings wherein like parts of the structure shown are designated by the same numerals in the several views, the sup-

porting frame for the sling 10 comprises a pair of parallelly spaced forward vertically disposed members 11, 12 and a pair of parallelly spaced rearward vertically disposed members 13, 14 all here shown as tubular in form and each provided with a foot 15.

A horizontally disposed rectangularly formed frame head 16, likewise formed of tubular stock, is supported on and fixedly secured to the upper ends of the frame members 11, 12, 13 and 14 and the upper lengths of each longer member of the frame head 16 is provided with a series of spaced pin receiving apertures 17 and with a series of spaced pin receiving apertures 18, each of the 15 opposite series of apertures 17, 18 being in lateral registration as best shown in Figure 3.

An arm rest 19 for the patient 20 is secured to the inner ends of a pair of inwardly converging tubular stock members 21, 22 whose outer ends 20 are vertically adjustably secured to the forward frame members 11, 12 in any suitable manner as by thumb screws 23 whereby the arm rest 19 may be selectively elevated or dropped within the discretion of the attending physician and 25 for the comfort of the patient who is to be encased within the cast.

A cross member 24 slidably disposed between the longer lengths of the rectangular frame head 16 is provided at its opposite ends with a pin receiving well adapted to register with any of the proximate series of pin receiving apertures 17 whereby a detachable pin 25 may longitudinally adjustably fix the cross bar as may be desired and a hanger 26 likewise slidably disposed 30 on each longer length of the rectangular frame head 16 is provided with a pin receiving well adapted to register with any of the proximate series of apertures 18 whereby each hanger may be longitudinally adjustably fixed to its length 35 of the frame head as may be required in a given instance by a detachable pin 27.

The sling 10 of any suitable flexible material such as canvas or other fabric and best shown in Figure 5 is bifurcated at its head end whose 45 spaced tongues 28 are adapted to accommodate the neck of the patient therebetween when in slung position, the arms being disposed on opposite sides of each tongue and supported on the adjustable arm rest 19 as best shown in Figures 50 1 and 2.

The outer end of each tongue 28 is provided with a hem 29 for suspending the head end of the sling by means of a pair of longitudinally adjustable straps 30, each secured to a pair of 55 spaced hangers 31 laterally adjustable on the

cross member 24 and the foot end of the sling is provided with a pair of spaced strap receiving grommets 32 each adapted to receive a longitudinally adjustable strap 33 secured to a cross bar 34 vertically adjustable on and between the rearward frame member 13, 14 by means of the thumb screws 35.

The side lengths of the sling 10 are provided with a pair of oppositely disposed laterally projecting tongues 36 intermediate their lengths but nearer the foot end of the sling which tongues are each provided with a strap receiving grommet 37 adapted to receive a longitudinally adjustable strap 38 whose other end is suspended from a longitudinally adjustable hanger 26.

The sling per se may of course be suspended from any suitable type of frame, the gist of the invention residing in a longitudinally adjustable sling provided with a bifurcated head adapted to accommodate the neck of the patient and whose tongues are adapted to be selectively elevated or dropped, a foot adapted to be selectively elevated or dropped—both adjustably controlling the degree and character of curvature of the fractured vertebra—and most important, the sling is provided with oppositely disposed lateral tongues to which vertically and horizontally adjustable suspending ligaments may be secured whereby rigid fixation of the knees of the patient may be maintained to effect the proper dorsal curvature of the spine which is essential to reduction which begins at the pelvis.

In use, the tongue portions 28 of the sling 10 which engage opposite sides of the neck of the patient 29 can be made to effect the greatest point of flexion at either the high, low or intermediate portion of the vertebral column by horizontally and vertically adjusting the sling, the degree and character of the arching of the fractured vertebra being essential in the obtaining of complete reduction. The close application to the body of the patient of the two rami or tongue portions 28 of the sling permits of a close fitting cast at the upper point or any of the three points of fixation which is highly desirable.

The use of the secondary sling or arm rest 19 is highly desirable since the arms of the patient when positioned not greater than 90 degrees abduction, permits of application of the cast without extension of the scapulae and latissimus dorsi muscles. The cast which is otherwise normally widened at this point because the arms of the patient are extended over the head fits snugly facilitating a much better reduction.

It will thus be seen that the fracture sling herein shown and described is well adapted for use in applying a close fitting cast to a patient suffering from the fracture of the vertebra; that the fracture sling permits of retention of the necessary extension of the patient at the upper point of any of the three points of fixation, (1) the pelvic brim anteriorly, (2) the site of fracture posteriorly, and (3) the region of the sternal notch anteriorly and superiorly; that the

opposite ends of the fracture sling may be both either elevated or dropped and lengthened or shortened to increase or decrease the degree and character of the arch of the vertebra of the

patient; that the fracture sling preferably includes a secondary sling adapted to allow the arms of the patient to remain in a position of comfort not greater than 90 degrees abduction thereby permitting a close fitting of the application of the cast without extension of the scapulae and latissimus dorsi muscles; that the fracture sling is highly efficient and convenient in its intended use; and, that the fracture sling is reasonably economical in manufacture.

15 While but one specific embodiment of the invention has been herein shown and described, it will be understood that certain details of the construction shown may be altered or omitted without departing from the spirit of the invention as the same is defined by the following claim.

I claim:

A fracture frame including spaced pairs of supporting legs and parallel longitudinal supporting members connected to the said pairs of legs and spacing them from each other, a longitudinally adjustable transverse bar mounted on said supporting members and extending therebetween, a longitudinally adjustable hanger on each supporting member mounted in spaced relation to the said transverse bar, a second transverse bar vertically adjustably mounted on and extending between one pair of legs, vertically adjustable arm rest supporting bars each mounted on one leg of the opposite pair of legs and extending horizontally inwardly toward the first mentioned pair of legs and having their inner ends terminate adjacent each other, an arm rest mounted on the adjacent free inner ends of the said supporting bars and substantially subjacent the first mentioned transverse bar, and a flexible sling having a bifurcated end adjustably vertically mounted at its bifurcated end to the first mentioned transverse bar, intermediate its length to the said hanger, and at its other end to the second mentioned transverse bar, whereby the patient may be received in a downwardly facing position on the sling with his neck disposed between the bifurcated end thereof, his arms supported on the arm rest at not greater than ninety degrees abduction, his knees positively fixedly supported in relation to and by the sling and the curvature of his spine adjusted as required.

NORMAN A. FLEISHMAN.
